UNITED STATES PATENT OFFICE.

SAMUEL N. SMITH, OF NEW YORK, N. Y., ASSIGNOR OF ONE-HALF TO HERMAN W. HOOPS, OF NEW YORK, N. Y.

MAGNETIC ORE-SEPARATOR.

1,161,351.

Specification of Letters Patent. Patented Nov. 23, 1915.

Application filed February 8, 1915. Serial No. 6,751.

To all whom it may concern:

Be it known that I, SAMUEL N. SMITH, a citizen of the United States, and a resident of New York city, borough of Manhattan, 5 in the county of New York and State of New York, have invented certain new and useful Improvements in Magnetic Ore-Separators, of which the following is a specification.

10 This invention relates to magnetic ore separators and more particularly to that class of magnetic ore separators which serve for removing or separating finely divided ore from its gangue by the hydraulic process or what are commonly known as wet process ore separators, as distinguished from separators which can be used only for separating ore that is perfectly dry.

The object of this invention is to provide 20 a new and improved wet process magnetic ore separator which is simple in construction, strong, durable and compact, effective and economical in use and is so constructed as to present the particles of ore in such a 25 manner that they can be rapidly and reliably separated from the gangue.

In the accompanying drawings in which like letters of reference indicate like parts in all the figures, Figure 1 is a longitudinal 30 sectional view of my new and improved magnetic ore separator. Fig. 2 is a detail view of the tension device for the endless apron. Fig. 3 is a plan view of the pan. Fig. 4 is a detail sectional view on the line 35 $x-x$ of Fig. 3.

The deposits of pulverized ore are usually found in the bottoms of rivers, bays and so forth and with the sand with which the ore is mixed, it is pumped up or dredged and delivered to the separator.

Between the front standards 1 of an upright frame 2 a magnetic drum 3 is mounted to rotate by gudgeons 4 and over the drum an endless apron 5 is passed, which 45 is preferably made of very heavy cotton fabric and this apron is also passed over a non-magnetic drum 6 mounted between the rear standards 7 of the frame. Between the drums 3 and 6 the upper run of the 50 apron is passed over a table 8 attached to the rear standards 7 and supported by arms 9 which are attached to the front standards 1. Between downwardly projecting arms 10 on the table 8, a roller 11 is mounted, over

which the bottom run of the apron passes 55 and is thus held raised.

A forked frame 12 is pivoted to the sides of the frame 2 and in the same a roll 13 is pivoted and the arms of the frame are united by a bar 14. A spring 15 is attached 60 to the bar 14 and to the underside of the table 8 and to an arm 16 projecting rearward from the frame 12 a weight 17 is attached. The spring and the weight serve for holding the apron 5 taut. A roller 18 65 mounted between arms 19 pivoted to the rear standards is pressed against that part of the apron passing over the bottom part of the rear drum by springs 32 for the purpose of squeezing off the particles of ore that 70 still adhere to the apron.

A pan 20 is mounted in the lower part of the frame. It is supported near its forward end by brackets 21 and at its rear is supported by arms 22 which can be adjusted 75 by screws. Within the pan 20, partitions or deflecting plates 23 are arranged. At or near the rear or closed end of the pan, each deflecting plate is connected with the side of the pan and is gradually inclined upward 80 toward the front. At its bottom edge it is hinged to the bottom of the pan and at its top, near the front, it is connected with a screw 24 for inclining the top of the plate inward, more or less. The front of the pan 85 is open and beneath the open end a gutter or belt conveyer 25 is arranged for carrying off the mixture of sand and water. 26 indicates in dotted lines a chute for delivering the mixture of ore, sand and water into 90 the pan.

A series of pipes 28 extending transversely under the pan and connected with a water supply pipe 29 are provided with numerous nozzles 30 passing through the 95 bottom of the pan. These nozzles are disposed at the sides of the pan and are inclined so as to discharge somewhat toward the sides of the pan. A deflector 34 diverts the water as it flows into the pan, and so assists the 100 jets in establishing a transverse circulation in the current.

The operation is as follows: A mixture of sand, finely divided ore and water is delivered into the pan 20 through the chute 26 105 or the pipe 31, it depending somewhat upon the nature of the ore delivered. The sand and ore are carried forward by the jets of

water, entering the pan from below through nozzles 30 and are thoroughly mixed and agitated and by the partitions or plates 23 are crowded toward the front of the pan where the magnetic drum is located. The particles of iron and iron ore are taken up by the drum and are carried by the belt, which travels over the drums from front to rear. The drums are suitably rotated by a belt as indicated or by a motor, etc. The top run of the apron is supported by the table 8 which prevents it from sagging under the weight of the ore. The ore drops off the apron as the same passes down on the rear roller or drum 6 and what ore still adheres is swept off by the squeezing roller 18. The apron passes up over the roller 11 and then down to the magnetic drum where it takes up ore again and so on. The sand, deprived 20 of its ore passes with the water out of the open, front end of the pan.

The machine is fed through a pipe 31 or the chute 26 which delivers water laden with the gangue to the pan 20.

25 32 is a guide for the apron which is placed so as to be tangent to the drum, 3. The table has flanges 33 for guiding the apron to the drum 6.

Having described my invention what I 30 claim as new and desire to secure by Letters Patent is:—

1. In a magnetic ore separator, the combination with drums, of which one is magnetic, of an endless apron passed over the 35 same, a pan closed at the rear end and open at the front end and having its front end below the magnetic drum, which extends into the same, and deflecting partitions projecting upward from the bottom of the pan, 40 which partitions are connected with the pan at the rear and gradually converge toward each other, substantially as set forth.

2. In a magnetic ore separator, the com-

bination with drums, of which one is magnetic, of an endless apron passed over the 45 same, a pan closed at the rear end and open at the front end and having its front end below the magnetic drum, which extends into the same, and deflecting partitions projecting upward from the bottom of the pan, 50 which partitions are connected with the pan at the rear and gradually converge toward each other and which partitions are hinged at the bottom and means for adjusting the deflectors to be inclined inward and upward, 55 substantially as set forth.

3. A magnetic ore separator including in combination a magnetic drum, a pan, means for supplying a vehicle bearing finely divided material to said pan, water jets discharging into said pan for maintaining the distribution of said material in said vehicle while flowing to said drum, and deflectors situated at each side of the pan for directing the water toward the center of the pan. 65

4. A magnetic ore separator including in combination a magnetic drum, a pan, means for supplying a vehicle bearing finely divided material to said pan, water jets discharging into said pan for maintaining the 70 distribution of said material in said vehicle while flowing to said drum, and adjustable deflectors situated at each side of the pan for directing the water toward the center of the pan. 75

5. A magnetic ore separator including in combination a magnetic drum, a pan, a feed pipe adapted to discharge water into said pan and means for so modifying the current as to produce a transverse circulation therein, said means including side jets and walls. 80
